UNITED STATES PATENT OFFICE.

CARL YAEGER, OF DETROIT, MICHIGAN, ASSIGNOR TO A. LAITNER & SONS, OF DETROIT, MICHIGAN, A COPARTNERSHIP COMPOSED OF EDWARD A. LAITNER, WALTER C. LAITNER, AND EMMA R. LAITNER.

BRUSH-MAKING MACHINE.

1,424,545.

Specification of Letters Patent. Patented Aug. 1, 1922.

Application filed October 25, 1920. Serial No. 419,281.

To all whom it may concern:

Be it known that I, CARL YAEGER, a citizen of the United States of America, residing at Detroit, in the county of Wayne and State of Michigan, have invented certain new and useful Improvements in Brush-Making Machines, of which the following is a specification, reference being had therein to the accompanying drawings.

10 This invention relates to brush making machines and more particularly to brush making machines wherein the bristles or the like are fed into engagement with a brush block through a suitable nozzle.

15 Machines of this type as heretofore constructed have employed a nozzle with a longitudinal slot in communication with the bristle passage to allow disengagement of each tuft of bristles from the nozzle by the 20 backward movement of the brush block after anchorage of such tuft therein. Because of this structural feature such machines have heretofore been limited in their use to the production of brushes having the bristles 25 bent at substantially a mid point so as to double the same in forming the tufts. It has not been feasible in the use of such machines to fold the bristles adjacent an end thereof for the reason that the short end 30 portions could protrude through said slot while being fed through the nozzle and consequently allow an escape of the bristles from proper engagement with the feeding means. Certain kinds of bristles used in 35 brush making are not, however, adapted to be doubled to form the tufts of the brushes, because of a lack of uniformity between the ends of the bristles. Such bristles may be coarse and stocky at one end and 40 relatively fine at the other. It has been necessary, heretofore, in using such non-uniform stock to resort to comparatively slow hand operations because of location of the fold adjacent one end of the bristles.

45 It is the object of the present invention to associate with the slotted nozzle of a brush making machine, a bristle retaining device that will permit folding of the bristles quite close to an extremity thereof without danger of the tuft falling apart as it is fed through the nozzle.

In the accompanying drawings:

Figure 1 is a front view of the tuft gath-

ering and feeding portion of a brush making machine, the tuft gatherer being shown 55 in its initial position as is likewise the mechanism for forcing the bristles through the nozzle;

Figure 2 is a similar view showing the tuft gatherer in its final position and showing 60 the lowermost position of the bristle feeding mechanism, in which position the bristles are being forced into the brush back.

Figures 3, 4, 5 and 6 are detail views 65 showing various positions assumed by the pivotal dog employed in the invention to establish a lost motion drive between two adjacent reciprocating parts;

Figure 7 is a cross section taken on line 70 7-7 of Figure 2;

Figure 8 is a side view of the nozzle of the machine with the bristle retainer in raised position, a tuft of bristles being shown in their initial position of engagement 75 with said nozzle.

In these views, reference character 1 designates a portion of the frame of a brush making machine which portion supports the tuft gathering and bristle feeding mechanism. 2 is a slide which is vertically reciprocatory in the member 1. 3 is a needle which depends from the slide 2, being clamped to the lower end of said slide by the plate 3^a. The needle 3 registers with the central passage 4 of the nozzle 5 and is adapted to force tufts of bristles, one of which is indicated at 6 in Figure 8, through said nozzle. The nozzle is clamped by a plate 7 to a projection 8 upon the frame 1 and depends from said projection as is clearly shown in the drawings. 9 indicates the oscillatory tuft gatherer which is pivoted as indicated at 10 upon an arm 11 projecting in front of the slide 2 from one side of the head 1. The member 9 comprises a segmental plate 10^a and the curved finger 11^a downwardly projecting from said plate and notched as indicated at 12. Said tuft gatherer is adapted to rock from the position shown in Figure 1 to that disclosed in Figure 2. In the former position the notch 12 is in communication with the feed box 13 from which the notch will be charged with bristles sufficient to form the desired tuft. By movement of the tuft

gatherer to the position shown in Figure 2, the charge of bristles in the notch 12 will be located above the nozzle 5 in a position to be forced through said nozzle upon lowering of the needle 3. The segmental portion 10 of the tuft gatherer retains the bristles in the feed box during swinging of said element. As the needle 3 is lowered to force the bristles 6 through the nozzle 5 the tuft gatherer returns to its initial position. The parts above briefly described are not novel, and a more detailed description and illustration of the same may be had if desired in United States Patents 845,957 of 15 March 5, 1907, and 846,583 of March 12, 1907.

The present invention consists in associating with the nozzle 5 a bristle retainer comprising a pair of reciprocating fingers 13^a 20 engaging the front and back of said nozzle so as to extend across the vertical slot 14 which opens from the front and rear faces of the nozzle into its bristle feeding passage. The front and rear faces of the nozzle are formed parallel as indicated at 15 so as to be snugly engaged by the fingers 13^a in the various positions of the latter. Also the head or top portion 16 of the nozzle is vertically slotted at 17 forwardly and rearwardly of the depending nozzle portion to adapt the fingers 13^a to enter said slot at the upper limit of their stroke as shown in Figure 8. The fingers 13^a are secured to the lower extremity of a cylindrical stem 18, the upper end of which is threaded as indicated at 18^a to engage the lower end of the rectangular plunger member 19. Said member has a reduced upper portion engaging a bearing 20 carried by the frame 1 adjacent to the top thereof and the stem 18 is provided with a bearing in the projection 8.

To establish a lost motion drive connection from the slide 2 to the plunger member 19, a dog 21 is pivoted at 22, upon a lug 23 carried by the plunger, said dog being located intermediate said plunger and the frame 1. A lug 24 carried by the upper portion of the slide 2 is adapted to engage the upper end of the dog 21 for actuating a downward travel of the plunger member during a portion of the downward stroke of said slide and a lug 24^a is adapted to similarly engage the lower end of the dog 21 during a portion of the upward stroke of the slide. Screw heads 25, stationary upon the frame 1, adjacent one edge thereof, are engageable with beveled faces 26 of the dog 21 to trip said dog out of engagement with the lugs 24 in the desired positions of the plunger 19.

Considering now the operation of the above described invention it is to be understood first that the bristle retainer comprising the fingers 13^a must be actuated down-

wardly to accompany the travel of the tuft of bristles through the nozzle 5, so as to prevent such protruding of the ends of the bristles through the slots 14 as would allow the scattering of the bristles. It is impossible, however, to allow the retainer 13^a to move downwardly the entire stroke of the needle 3 since said needle must project a certain distance below the nozzle 5 to force the bristles into the bores of the brush back. Thus in Figure 2 there is shown at 27, a brush back into which the needle is projected. It is necessary to immediately return the bristle retainer to the upper portion of the nozzle after anchorage of a tuft of bristles in a brush back so as to leave the lower portion of the slot 14 unobstructed to permit the disengagement of the tuft from the nozzle through said slot.

It is not feasible however to shift the retainer 13^a upwardly to the upper limit of the stroke of the needle 3 since the latter is required to rise some distance above the nozzle to engage a staple to be formed from a wire 27^a which is advanced by means (not shown) into the staple forming chamber 28. These requirements are met by the lost motion connection between the slide 2 and plunger 19 which has been described. In other words, when movement of the slide 2 has brought a staple into engagement with a tuft of bristles above the nozzle 5 and is about to feed said tuft and staple into the nozzle, the uppermost lug 24 engages the upper dog 21 as shown in Figure 3, and downward travel of the bristle retainer is initiated in unison with the downward travel of the bristle. As the retainer 13 approaches the lower end of the nozzle 5 as shown in Figure 2, the beveled face 26 at the lower end of the dog 21 engages the lowermost screw head 25 effecting a tripping of said dog to disengage the same from the lug 24 thus leaving the retainer 13^a stationary during the balance of the downward travel of the needle 3. When the slide 2, needle 3 are again raised the retainer 13^a remains stationary until the lower lug 24^a engages the lower end of the dog 21, and the upward travel of the retainer effected through such an engagement continues until the retainer has been engaged in the slots 17 as indicated in Figure 8. At this time the dog 21 is tripped through engagement of the upper beveled face 26 of the dog 21 of the upper screw head 25 so that the final portion of the upward stroke of the slide 2 occurs independently of the retainer 13^a and plunger 19.

It has been found that through employment of the described bristle retainer in association with the slotted nozzle of a brush making machine it is possible to use bristle stock only very slightly longer than the tufts to be formed without any undesirable 18

resulting looseness in the bristles or falling apart of the tuft as it is fed through the nozzle.

What I claim as my invention is:

5. 1. In a brush making machine, the combination with a bristle feeding nozzle having a longitudinal slot into its bristle feeding passage for disengagement of a tuft of bristles from the nozzle subsequent to anchoring of such tuft in a brush back, of means for delivering bristles to said nozzle, means for forcing the bristles through the nozzle and inserting them into a brush back, a member in proximity to said longitudinal slot of the nozzle providing an abutment for the bristles in their passage through the nozzle to prevent the bristles projecting through said slot, and means for moving said member in timed relation with the means for forcing the bristles through the nozzle to permit disengagement of the bristles through said slot after engagement of the bristles with the brush back. 75
10. 2. In a brush making machine, the combination with a bristle feeding nozzle, having a longitudinal slot into its bristle feeding passage for disengagement of a tuft of bristles from the nozzle subsequent to anchoring of such tuft in a brush back, of means for delivering bristles to the nozzle, means for forcing bristles through the nozzle and inserting them into a brush back, a member in proximity to said slot of the nozzle providing an abutment for the bristles in their passage through the nozzle to prevent their protruding through said slot, and mechanism actuating travel of said abutment in unison with the bristles during feeding of the same through the nozzle. 80
15. 3. In a brush making machine, the combination with a bristle feeding nozzle having a longitudinal slot into its bristle feeding passage for disengagement of a tuft of bristles from the nozzle subsequent to anchoring of such tuft in a brush back, of means for periodically delivering bristles to the nozzle, reciprocating means timed with relation to said bristles delivering means for feeding the bristles through the nozzle and inserting them into a brush back, a member in proximity to the slot of said nozzle providing an abutment for the bristles in their passage through the nozzle to prevent their protruding through said slot, and means for reciprocating said member in unison with the tuft feeding member during a portion of the stroke. 105
20. 4. In a brush making machine, the combination with a bristle feeding nozzle having a longitudinal slot into its bristle feeding passage for disengagement of a tuft of bristles from the nozzle subsequent to anchoring such tuft in a brush back, of means for periodically delivering bristles to the nozzle, a reciprocatory member engageable with the nozzle for feeding the bristles therethrough and into a brush back, means for actuating said reciprocating member in timed relation to the bristle delivery means, a member in proximity to said slot of the nozzle providing an abutment for the bristles in their passage through the nozzle to prevent their protruding through said slot, and a movable member for actuating the abutment member in unison with the bristle feeding member during a portion of the stroke. 110
25. 5. In a brush making machine, the combination with a bristle feeding nozzle having a longitudinal slot into its bristle passage for disengagement of a tuft of bristles from the nozzle subsequent to anchoring of such tuft in a brush back, of means for delivering bristles to the nozzle, a reciprocatory member for feeding the bristles through the nozzle, a slide actuating said reciprocatory member, a member in proximity to said slot of the nozzle providing an abutment for the bristles in their passage through the nozzle to prevent their protruding through said slot, a stem carrying said member extending adjacent said slide, a movable member for actuating the stem during intermediate portions of a stroke of the slide, whereby the bristle retaining member accompanies the bristles downward in their passage through the nozzle and is raised subsequent to anchorage of the tuft in a brush block to permit disengagement of the tuft from the nozzle through said slot. 115
30. 6. In a brush making machine, the combination with a bristle feeding nozzle having a longitudinal slot in its bristle feeding passage for disengagement of a tuft of bristles from the nozzle subsequent to anchoring of such a tuft in a brush back, of means for delivering bristles to the nozzle, a reciprocatory member for feeding the bristles through the nozzle and inserting them into a brush back, a slide actuating said reciprocatory member, a member in proximity to said slot of the nozzle, providing an abutment for the bristles in their passage through the nozzle to prevent their protruding through said slot, a stem carrying said member, said stem and slide forming adjacent members, a dog pivoted intermediate upon one of said members, projections upon the other of said members engageable by the respective end portions of said dog for actuation of the stem upwardly and downwardly, and means for tripping said dog to establish a drive to the stem during an intermediate portion only of the stroke of the slide. 120
35. 7. In a brush making machine, the combination with a bristle feeding nozzle having a longitudinal slot into its bristle feeding passage for disengagement of a tuft of bristles from the nozzle subsequent to anchoring of such a tuft in a brush back, of 125
40. 8. In a brush making machine, the combination with a bristle feeding nozzle having a longitudinal slot into its bristle feeding passage for disengagement of a tuft of bristles from the nozzle subsequent to anchoring of such a tuft in a brush back, of means for delivering bristles to the nozzle, a reciprocatory member for feeding the bristles through the nozzle and inserting them into a brush back, a slide actuating said reciprocatory member, a member in proximity to said slot of the nozzle, providing an abutment for the bristles in their passage through the nozzle to prevent their protruding through said slot, a stem carrying said member, said stem and slide forming adjacent members, a dog pivoted intermediate upon one of said members, projections upon the other of said members engageable by the respective end portions of said dog for actuation of the stem upwardly and downwardly, and means for tripping said dog to establish a drive to the stem during an intermediate portion only of the stroke of the slide. 130

- means for delivering bristles to the nozzle, a reciprocatory member for feeding the bristles through the nozzle and into a brush back, a slide actuating the reciprocatory member, a member in proximity to said slot of the nozzle providing an abutment for the bristles in their passage through the nozzle to prevent their protruding through said slot, a stem carrying said member, said 10 stem and slide forming adjacent members, a dog intermediately pivoted upon one of said members, projections upon the other of said members engageable respectively by the extremities of a dog for actuating the stem 15 upwardly and downwardly, stationary projections engageable with said dog to trip the same in predetermined positions of the stem, and a spring engageable with the dog in one limiting position of the stem to urge said 20 dog into proper position for engagement by the corresponding projection.
8. In a brush making machine, the combination with a slotted bristle feeding nozzle, an oscillatory bristle gatherer for the 25 nozzle and a reciprocatory needle for forcing the bristles through the nozzle, of means engaging said nozzle and adapted to accompany said needle during a portion of its travel through said nozzle to retain the protruding ends of the bristles within the slot 30 of said nozzle.
9. In a brush making machine the combination with a slotted bristle feeding nozzle, an oscillatory bristle gatherer for the 35 nozzle and a reciprocatory needle for forcing the bristles through the nozzle, of a reciprocatory member embracing opposite sides of the said nozzle and adapted to accompany said needle during a portion 40 of its travel through said nozzle to retain the protruding ends of the bristles within the slot of said nozzle.
10. In a brush making machine, the combination with a frame, a slotted bristle feeding nozzle carried by the frame, a reciprocatory slide in said frame, an oscillatory bristle gatherer for the nozzle and a reciprocatory needle for forcing the bristles 45 through the nozzle, of a member engaging said nozzle to retain the protruding ends of the bristles within the slot of said nozzle,
- 5 a stem secured to said member, a plunger removably secured to said stem, a dog pivotedly mounted upon the plunger, means carried by the slide for alternately engaging the opposite ends of the dog to actuate the plunger upwardly and downwardly, and means carried by the frame adapted to trip the dog out of engagement with said actuating means at a predetermined point during the 10 upward and downward movement of the plunger.
11. In a brush making machine, the combination with a bristle feeding nozzle having a longitudinal slot in its bristle feeding 55 passage for disengagement of a tuft of bristles from the nozzle subsequent to anchoring said tuft in a brush back, of means for delivering bristles to the nozzle, means for forcing bristles through the nozzle and 60 inserting the same into a brush back, a member in proximity to the slot of the nozzle providing an abutment for the bristles in their passage through the nozzle to prevent their protruding through said slot, and 65 means for moving said member longitudinally of the nozzle in timed relation with the means for forcing the bristles through the nozzle to permit disengagement of the bristles from the nozzle through said 70 slot after engagement of said bristles with a brush back.
12. In a brush making machine, the combination with a frame, a slotted bristle feeding nozzle carried by said frame, a reciprocatory slide in said frame, an oscillatory bristle gatherer for the nozzle and a reciprocatory needle for forcing the bristles through the nozzle, of a member engaging 75 said nozzle to retain the protruding ends of the bristles within the slot of said nozzle, a stem carried by said member, a plunger carried by said stem, a movable member upon said plunger, means on the slide for alternately engaging the opposite ends of 80 said movable member to actuate said plunger, and means on the frame adapted to trip the movable member out of engagement with said actuating means at a pre-determined point during the movement of said plunger. 100

In testimony whereof I affix my signature.
CARL YAEGER.
